COMBINED NAPKIN AND STRAW DISPENSER
AND BOTTLE CAP RECEPTACLE

John MacBell, Mobile, Ala.

Application December 9, 1954, Serial No. 33,466

Term of patent 14 years

(Cl. D44—24)

FIG. 1.

FIG. 2.

FIG. 3.

FIG. 4.

FIG. 5.

FIG. 6.

To all whom it may concern:

Be it known that I, John MacBell, a citizen of the United States of America, residing in Mobile, Mobile County, Alabama, have invented a new, original, and ornamental Design for a Combined Napkin and Straw Dispenser and Bottle Cap Receptacle, of which the following is a specification, reference being had to the accompanying drawing, forming part thereof, in which:

Figure 1 is a perspective view of a combined napkin and straw dispenser and bottle cap receptacle showing my new design;

Figure 2 is a fragmentary perspective view of the opposite side of the device;

Figure 3 is a top plan view of the device;

Figure 4 is a left side elevational view of the device;

Figure 5 is a front elevational view of the device; and Figure 6 is a right side elevational view of the device. I claim:

The ornamental design for a combined napkin and straw dispenser and bottle cap receptacle, as shown.
